APPARATUS FOR CONCENTRATION OF MINERALS AND LIKE MATERIALS

Frank C. Peterson, Oakland, Calif.

Application March 12, 1940, Serial No. 323,553

6 Claims. (Cl. 209—455)

This invention relates to an apparatus for concentration of minerals and like materials by jig operation.

A pulsating type of jig is not a new device. It has been used for many years in coal classifying, tin concentration, and other material separations. In recent years it has been adapted to gold mining operations, replacing the riffle and table in many instances.

The jig most extensively used in the gold mining industry consists of a displacement diaphragm mounted in the bottom or sides of a square or rectangular tank, the top of which is covered with a coarse wire screen basket called the "grid." This basket is from two to six inches deep and is partially filled with steel shot from $\frac{1}{8}$ to $\frac{1}{4}$ inch in diameter. The tank is mounted in the sluice circuit with the top of the basket level with the bottom of the sluice, and has no grade. Water is admitted to the tank from an outside source, flowing upwardly through the shot bed, which gives an undercurrent effect. As the diaphragm is moved, the water velocity is increased on the up-stroke, and suction is applied to the bed on the down-stroke. The diaphragm displacement is greater than the amount of water admitted. This action gives first a loose and then a tight bed condition, moving the heavier material from the overflowing gangue into the tank by progressive steps. The greatest disadvantage of this method is that the bed is held closed not only by its own weight but by added suction as well, for a period of fifty per cent of the time, thus causing the bed to solidify itself to a density prohibiting the lodging of other material which is continuously flowing over it and thereby obviously reducing efficiency.

The mechanical connection of the diaphragm usually consists of a cam, crank or eccentric with a connecting rod which is guided with a cross head. As the load of water and sand is heavy, a great deal of power is required for rapid oscillation, with resultant wear on the connecting devices. Some manufacturers have mounted two diaphragms on a rocker or walking beam to lessen the power demand. This however does not lessen the load on the connecting rods, bearings and cross heads. They must be heavily constructed and well lubricated, if reasonable durability is to be expected.

The type of jig just described is commonly known as a "rounger" or "low ratio" concentrator, operating from one hundred to two hundred strokes per minute. The stroke length 55 efficiency.

varies from $\frac{3}{4}$ inch to $1\frac{1}{2}$ inches, depending upon the requirements of the operation.

The material from this Jig is delivered to a second Jig operating at a faster speed and shorter stroke, which reconcentrates to a higher ratio, and is termed a "cleaner" or "finishing Jig." From here the material goes to a polishing device, if coated or rusted gold is present, then it goes to an amalgamator. The entire transaction requires at least three, and many times four and five, operations to recover the gold from the gangue. As the rougher Jig is the only unit in the circuit having contact with the gold-carrying gangue, the main recovery rests with the rougher Jig. If the rougher Jig permits gold to pass, there is no way to prevent its loss. Furthermore, the successive steps following the rougher Jig are not 100% efficient.

In handling certain materials a large percentage of the gold content is of a minute and flaky type. This prevails high in the gangue and is resistant to concentration. It is these values which cause heavy losses in many mining operations.

During several years of continuous experimentation many factors have been revealed which have heretofore been unknown, or at least unrecognized. These are as follows:

(1) Materials of different specific gravities and size respond to different vibrations or pulsations of the water passing through the grid bed.

(2) Impact delivered to the gangue by the pulsating water promotes concentration.

(3) Water dilution must be varied to gain the greatest recovery.

(4) The points at which gold and other values will synchronize with the pulsation of water are much higher than two hundred strokes per minute.

(5) The grid bed must be loose and receptive to the heavier materials at all times, and not held tightly closed by weight and suction action half of the time.

(6) Water must flow upwardly through the grid bed in sufficient quantity to classify, and little if any must be drawn from the overflowing sluice in a reverse direction through the grid bed.

(7) Impact delivered to the water travels at equal speeds in all directions, thus determining the shape of the hutch or tank as round.

(8) The greatest velocity of flow of material in a sluice is in the center, and it accordingly requires a round recovery bed for maximum efficiency.

The object of the present invention is to provide a jig which is so constructed and operated that the factors or discoveries above set forth may be fully utilized. The jig or apparatus employed is shown by way of illustration in the accompanying drawings, in which

Fig. 1 is an enlarged central vertical section of the pulsating head and the mechanism operating the same;

Fig. 2 is a cross section of the jig, taken on the line II—II of Fig. 3;

Fig. 3 is a side elevation of a sluice, partially in section, showing the position and arrangement of a plurality of jigs; and

Fig. 4 is a plan view of Fig. 3.

Referring to the drawings in detail, and particularly Figs. 2, 3 and 4, A indicates a sluice box, in the bottom portion of which is formed a depression B and below which are mounted the hatches C, D and E of three jigs which are identical in construction and operation. Each hutch is cylindrical in shape and is provided with a sloping bottom section 2, at the lower end of which is mounted a discharge spigot which permits intermittent or continuous discharge of concentrates. The jig or concentrating bed of each hutch is formed in the depressed portion of the sluice, and is substantially identical to jig beds in common use, as the bottom of the bed consists of a coarse screen or grid, on top of which is placed steel shot varying in diameter from $\frac{1}{8}$ inch to $\frac{1}{4}$ inch. The depth of the bed may vary from two to six inches, depending on the type and quantity of material to be handled.

The water flow through the bed is in several respects different from common practice, as the flow is substantially continuous in a direction upwardly through the bed, and at the same time an impulse of comparatively high frequency is imparted to the water by impact action. The frequency of the impact will, however, vary in the different hatches, as the frequency in the first hutch will be the lowest and that in the last hutch will be the highest.

The mechanism whereby impact or pulsating movement is imparted to the water is identical in each hutch, and is best illustrated in Figs. 1 and 2. It comprises a stationary piston rod 6, secured by a coupling 7 to the upper end of a tube 8 which extends through the bottom of the hutch. Secured to the upper end of the rod 6 is a cup leather 9, snugly fitting the interior of a cylinder 10 which is free to reciprocate with relation to the stationary cup leather and rod. The cylinder is provided with an upper head 11 and a lower head 12, said cylinder and heads normally assuming the position shown in Fig. 1 due to the provision of a compression spring 14 interposed between the cup leather and the lower head.

Air under pressure from any suitable source is intermittently admitted and exhausted to impart reciprocal movement to the cylinder. This is accomplished as follows: Formed in the piston rod is a central passage 15 in which is secured a sleeve 16. Slidably mounted in the sleeve is a valve 17 whereby an air inlet port 18 and an exhaust port 19 are intermittently opened and closed.

Secured to the upper cylinder head is a hanger 20, and extending through said hanger and the valve is a threaded rod 21, the upper end of which is provided with a head 22. Springs 23 and 24 are interposed between the head and hanger and the valve, respectively, to insure seat-

ing of the valve and to cushion movement between the hanger and the rod head. When air under pressure is admitted through the inlet port it flows upwardly around the hanger into the space 25 formed between the cup leather and the head 11 of the cylinder, thereby causing upward movement of the cylinder and, at the same time, compression of the spring 14. As the cylinder moves upwardly the hanger moves with it, spring 23 becomes compressed, and the valve will also move, causing the inlet port to close and the exhaust port to open. With the opening of the exhaust port the air under pressure instantly escapes, and as the spring 14 is under compression, the cylinder is forced downwardly to its lowermost position. With the lowering of the cylinder the valve is also lowered, and the cycle of operation is repeated.

The diameter of the cylinder employed is so small that the area presented to the water in the hutch would not be sufficient to impart the desired impact or pulsating movement required. For this reason a cone-shaped head 27 of comparatively large diameter is secured to the head of the cylinder, and in order that water may be excluded from the mechanism, an annular diaphragm made of rubber is secured to a flange 27a of the head and to a similar flange 28 which in turn is secured to the stationary piston rod. By providing a head such as shown at 27, any desired area and impact action may be obtained.

The rapidity or frequency of the impact action depends entirely upon the length of stroke and the air pressure employed. A short stroke and high air pressure give the highest frequency and impact action. Conversely, a lower pressure and a longer stroke will give a lower frequency and impact. The air pressure or speed with which the air is admitted may be controlled by various means, for instance by a valve 29. The stroke is regulated by inserting a screwdriver and rotating the threaded rod which extends through the valve. By rotating the rod to raise the head 22 in the hanger, the stroke is lengthened, and by lowering the head in the hanger the stroke is shortened. Also, it is possible to produce a comparatively slow upward stroke by the slow admission of air or reduction of pressure, and to insure a rapid return stroke by use of the spring 14.

In actual practice, I prefer to employ two or more hatches, as shown in Fig. 3, and to supply each hutch with water from a pipe such as shown at 30 in Fig. 2. Each pipe is provided with a valve 31, and the flow of water upwardly through each hutch and the concentrating bed disposed above the same may thus be separately controlled. The pulsating mechanism in each hutch is also separately adjustable and may be regulated so that the first hutch operates with the lowest frequency and the last with the highest frequency. The frequencies employed may range from two hundred pulsations per minute to one thousand or more, depending upon the character of the material being handled, the size and specific gravity of the concentrates, etc.

Suffice it to say that I have discovered that materials of different size and specific gravity respond to different vibrations or pulsations, and it is for this reason that I employ a series of jigs operating at different frequencies. By placing the impact or pulsating mechanism high in the hutch, just below the grid bed, power demand is reduced, as the hydrostatic head against which the impacting mechanism operates is low. Fur-

ther, by being placed close to the bed, the impact is delivered directly to the gangue, and no excess water is moved. As all hutes are independently controlled, water dilution increases with each jig.

Due to the high pulsations and the rapidity of the down-stroke, the water flow is not only pulsating but the direction of flow is upwardly, thereby maintaining a jig bed which is soft and permeable to permit rapid settling of the concentrates. The impact delivered to the water travels at equal speeds in all directions, thus determining the cross sectional shape of the hutes as round. The hutes are close together and are covered with one continuous jig bed with a grade down stream. This grade is formed into steps by the cross partition plates 40 employed, and I thereby obtain the well known riffle effect.

While certain features of the present invention have been more or less specifically described and illustrated, I nevertheless wish it understood that various changes may be resorted to within the scope of the appended claims; and similarly that the materials and finish of the several parts employed may be in accordance with the experience and judgment of the manufacturer.

Having thus described and illustrated my invention, what I claim and desire to secure by Letters Patent is:

1. In a jig of the character described, a hutch having a jig bed disposed over the same, means for feeding water into the hutch and for discharging it up through the bed, a head member disposed below the bed in close proximity thereto, a cylinder secured to the head, a stationary piston within the cylinder, and a valve for admitting and exhausting air under pressure from the cylinder to impart a reciprocal movement to the cylinder head.

2. In a jig of the character described, a hutch having a jig bed disposed over the same, means for feeding water into the hutch and for discharging it up through the bed, a head member disposed below the bed in close proximity thereto, a cylinder secured to the head, a stationary piston within the cylinder, a valve for admitting and exhausting air under pressure from the cylinder to impart a reciprocal movement to the

cylinder head, and means actuated by movement of the cylinder for opening and closing the valve.

3. In a jig of the character described, a hutch having a jig bed disposed over the same, means for feeding water into the hutch and for discharging it up through the bed, a head member disposed below the bed in close proximity thereto, a cylinder secured to the head, a stationary piston within the cylinder, a valve for admitting air under pressure to impart movement to the cylinder in one direction, and a spring for returning the cylinder.

4. In a jig of the character described, a hutch having a jig bed disposed over the same, means for feeding water into the hutch and for discharging it up through the bed, a head member disposed below the bed in close proximity thereto, a cylinder secured to the head, a stationary piston within the cylinder, a valve for admitting air under pressure to impart movement to the cylinder in one direction, a spring for returning the cylinder, means actuated by movement of the cylinder for opening and closing the valve, and an exhaust port actuated by the valve.

5. In a jig of the character described, a hutch having a jig bed disposed over the same, means for feeding water into the hutch and for discharging it up through the bed, a head member disposed below the bed in close proximity thereto, a cylinder secured to the head, a stationary piston within the cylinder, a valve for admitting and exhausting air under pressure from the cylinder to impart a reciprocal movement to the cylinder head, and an annular, flexible diaphragm connecting the piston and head to exclude water from the piston and cylinder.

6. In a jig of the character described a hutch having a bottom and a jig bed disposed over the same, means for feeding water into the hutch and for discharging it up through the bed, a tube extending through the bottom and upwardly into the hutch, a flanged member secured on the upper end of the tube, a head member covering the tube and flange, an annular flexible diaphragm secured to the head and the flange to exclude water, and means for imparting a vertical reciprocal movement to the head.

FRANK C. PETERSON.
